(57) **CLAIM**

We claim the ornamental design for a tool pouch with retractor compartments, as shown and described.

DESCRIPTION

FIG. 1 is a front, left perspective view of a tool pouch with retractor compartments in a closed position showing our new design.

FIG. 2 is a front, right perspective view thereof.

FIG. 3 is a top plan view thereof.

FIG. 4 is a bottom plan view thereof.

FIG. 5 is a left side elevation thereof.

FIG. 6 is a right side elevation thereof.

FIG. 7 is a rear, right perspective view thereof.

FIG. 8 is a rear, left perspective view thereof.

FIG. 9 is front elevation thereof.

FIG. 10 is a rear elevation thereof.

FIG. 11 is a front, left perspective view of the tool pouch of FIG. 1 showing the retractor compartments in an open position.

FIG. 12 is a front, right perspective view the tool pouch of FIG. 1 showing the retractor compartments in an open position; and,

FIG. 13 is a front elevation the tool pouch of FIG. 1 showing the retractor compartments in an open position.
